BURNER CONTROL SYSTEM

Burton E. Shaw, Bristol, Ind., assignor to Penn Electric Switch Co., Goshen, Ind., a corporation of Iowa

Application April 14, 1941, Serial No. 388,564

5 Claims. (Cl. 158—28)

My present invention relates to a burner control system including a low voltage protection feature and a combustion temperature switch of the type disclosed in the Rothwell and Wagner application, Serial No. 378,150, filed February 10, 1941, which eliminates the necessity of the usual "slip" or "friction" connection used in present-day "stack" switches.

One object of my invention is to provide a protection system of simple and inexpensive construction for burner control circuits.

A further object is to provide in connection with a burner control circuit, a protection feature particularly for low voltage wherein a single relay or the like is operable to cut in at as low as eighty percent of the full line voltage and to cut out at a point not lower than approximately sixty-five percent of the full line voltage, whereas in the usual systems in which relays are used for burner control circuits, the relay when properly designed to give sufficient motion for operation of the contacts cuts out at about thirty-five percent of the full line voltage. This is particularly important because at about sixty percent of the full line voltage the burner functions improperly, its efficiency is low, the air velocity and oil pressure being decreased and the opening of the solenoid or pressure regulating valve which usually controls the oil supply is restricted. Also, low voltage in the ignition transformer occurs, which causes entire loss of or at least irregular spark. This results in the burner "popping," and sometimes in an explosion.

The problem is particularly present in small localities when current consumption varies greatly, and in most of the localities when sleet gathers on the transmission wires and causes a temporary drop in voltage which may last for sometimes an hour or more. It is therefore obvious that cut out of the relay at or above sixty-five percent of the full line voltage is desirable.

A further object of my invention is to provide a relay which can be cut in at one voltage and thereafter maintained in the cut-in position by a reduced voltage, so that it is easier to drop out upon subsequent line voltage drop and the dropping out of the relay will occur before an excessive drop in the full line voltage occurs, whereas if the initial current supply, instead of a reduced current supply due to such reduced voltage, were maintained for keeping the relay energized, the line voltage at which the relay drops out would be excessively low.

Still a further object is to provide a combustion switch in the control system which is ex-

tremely simple in construction and inexpensive to manufacture and which may be arranged to respond to combustion by exposing a certain bimetal of the combustion switch to heat radiated from the combustion chamber, it being unnecessary to locate the thermostat inside a stack or the like, or inside the combustion chamber, but merely externally of the chamber with an opening through the wall of the chamber to expose the bimetal element to the heat therein.

With these and other objects in view, my invention with respect to its features which I believe to be novel and patentable will be pointed out in the claims appended hereto. For a better detailed understanding of the invention, and further objects relating to details of economy of my invention, reference is made to the following description and to the accompanying drawing wherein such further objects will definitely appear, and in which

Figure 1 is an electrodiagrammatic view of a burner control system embodying my invention, the combustion switch being shown in cold position;

Figures 2, 3 and 4 show, respectively, the combustion switch in the hot, initial combustion failure, and combustion failure after established, positions;

Figure 5 is a diagrammatic view of a portion of Figure 1 showing a slight modification, with the burner in non-operating position, and

Figures 6 and 7 are views of a holding switch of Figure 5 in an intermediate and in a running position, respectively.

On the accompanying drawing, I have used the reference character BM to indicate a burner motor and B a burner operated thereby. Ign indicates ignition mechanism for the burner B. A motor switch MS controls energization of the burner motor and the ignition mechanism, with current being supplied through wires 19 and 20. The wires 19 and 20 also extend to the primary P of a transformer T.

A room thermostat RT is illustrated and a control circuit therefor is energized initially from the entire secondary S of the transformer T. The initial secondary circuit includes combustion switch contacts 14 and 15, a relay coil RC and a safety heater H. The combustion switch for the contacts 14 and 15 is indicated generally at CS and includes a pair of bimetal elements 10 and 12 anchored as to a support 13 of insulating material. The contacts 14 and 15 are carried by the bimetal elements 10 and 12, respectively.

The bimetal element 10 carries a support 16

for a permanent magnet 17 which is adapted to cooperate, for a purpose which will hereinafter appear, with an armature 18. The armature 18 is carried by the bimetal element 12. The combustion switch CS is preferably mounted just outside a combustion chamber CC with an opening 11 in the wall of the chamber to permit radiation of combustion heat to the element 10.

The transformer T has its secondary coil S provided with a center tap indicated at 24. A holding switch HS is connected with the tap 14 and with the room thermostat or control circuit at a point intermediate the heater H and the relay coil RC. The holding switch HS is adapted to be closed by the relay coil RC whenever it is energized and the motor switch MS is adapted to be likewise closed.

In Figures 5, 6 and 7, I show a modified arrangement wherein a holding switch HS' takes the place of the holding switch HS and includes a pair of stationary contact blades 21 and 22, and a movable blade 23. The movable blade 23 normally assumes the position shown in Figure 5 but upon energization of the relay coil RC is moved thereby to the position of Figure 7. In passing from the position of Figure 5 to the position of Figure 7, the intermediate position of Figure 6 is assumed wherein the contacts of the holding switch HS' overlap.

PRACTICAL OPERATION

FIGURES 1 TO 4

Normal burner operation

With the combustion switch in the cold position of Figure 1, closure of the room thermostat effects energization of the relay coil RC and the heater H through the combustion switch contacts 14 and 15 from the entire secondary S of the transformer T. Energization of the relay coil effects closure of the motor switch MS, whereby the burner motor BM and the ignition mechanism Ign of the burner are energized.

Energization of the relay coil RC also closes the holding switch HS so that instead of the initial room thermostat or control circuit, two circuits are established as follows:

(1) The lower half of the secondary S supplies current to the heater H;

(2) The upper half of the secondary S supplies current to the relay coil RC through the room thermostat and the combustion switch contacts 14 and 15.

Assuming the secondary voltage to be 25, there are twenty-five volts available for causing cut-in of the relay when the thermostat closes. The parts are so designed that the relay can cut-in at eighty-five percent of this value so that the relay is thus operable at anywhere above eighty per cent of the full line voltage supplied to the primary P.

As soon as the holding switch HS is closed by energization of the relay, the circuits 1 and 2 mentioned above are established and obviously are weaker than the initial current from the entire secondary S. Consequently, the gaps in the relay can be quite wide and yet the relay will cut-out upon only a substantially small drop in the normal line voltage.

Energization of the heater H causes the bimetal element 12 to be heated and thereby warped, but this is a relatively slow process. Accordingly, the bimetal element 12 does not warp enough to separate the contact 15 from the contact 14 before combustion chamber temperatures start warping

the bimetal element 10 so that the contact 14 follows up the contact 15, as in Figure 2. The magnet 17 and the armature 18 also aid in keeping the contacts 14 and 15 engaged. The bimetal elements 10 and 12 may be placed under some initial tension when mounted on the insulating block 13, if it is desirable to eliminate the armature and magnet.

Subsequently, when the room thermostat opens, the relay coil is de-energized to thereby open the motor switch and stop the burner. The parts 10 and 12 will then cool down to their initial positions as in Figure 1 for another burner operating cycle.

15 Failure of combustion to be established

Referring to Figure 3, if combustion does not occur in the normal manner, the bimetal element 10 will remain in its cold position while the bimetal element 12 will move to its hot position, due to energization of the heater H. This will take preferably about a minute or so, although the time does not have to be as long as it takes the usual safety switch in a stack switch installation to trip out. The relay coil circuit is now opened across the combustion switch contacts 14 and 15 so that the relay coil is deenergized, thus opening the motor switch and the holding switch. After a time period predetermined by the length of time it takes the heater H and the bimetal element 12 to cool down, the room thermostat circuit will be reestablished, thus providing a purging period and thereafter permit an attempt at another start of the burner.

30 35 Combustion failure after combustion has been established

Referring to Figure 4, combustion has been established, thus moving the parts of the combustion switch to the position of Figure 2, and then combustion has failed so that the bimetal element 10 begins to bend back toward its original position, due to cooling down of the combustion chamber. Accordingly, the contact 14 will leave the contact 15 when the energy built up by straightening of the bimetal element is sufficient to overcome the pull of the magnet 17 on the armature 18. The contacts 14 and 15 thereupon open with snap action. The relay coil is now de-energized so that the motor switch opens and a purging period will be provided, during which the elements 10 and 12 cool to their initial positions. The contacts 14 and 15 are thereupon re-engaged to recycle the burner.

55 The combustion switch CS is a combined combustion switch and safety switch in that the contacts 14 and 15 are separated as a result of a cold combustion chamber CC and a hot heater H. Whenever these two events occur at the same time, then the burner is shut down for a purging period and recycling. As long as the burner operates on normal cycles, the contacts 14 and 15 remain engaged and are never separated. Separation occurs only when there is either an initial combustion failure or a combustion failure 60 subsequent to combustion establishment.

FIGURES 5, 6 AND 7

70 The system shown in these figures operates in substantially the same manner as described in connection with Figures 1 to 4 with the difference that energization of the relay coil effects reduction of the current supplied thereto for protection purposes by the double-throw holding switch HS'. The initial room thermostat circuit is from the bottom of the secondary S through the re-

lay coil, the heater, the combustion switch and the room thermostat to the top of the coil S. Energization of the relay coil positions the holding switch H₅ as in Figure 7 so that, instead of the initial circuit, there is then a circuit through the relay coil, the heater, the combustion switch and the room thermostat, with the elements 22 and 23 in such circuit and the upper half of the secondary S entirely out of the circuit. The overlapping of the contacts, as in Figure 6, prevents any opening of the relay coil circuit which would permit it to revert to initial position during change-over.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. A burner control system comprising a burner, a motor for operating said burner, an operating circuit for said burner including a motor switch, a source of current for said circuit, a transformer connected with said source and having a tapped secondary, a room thermostat, a circuit therefor, combustion switch contacts and a safety heater in said circuit, a combustion switch including said combustion switch contacts and a pair of exposed bimetal elements, one responsive to heat of the combustion chamber and located entirely outside of it, the combustion chamber having an opening through which heat is radiated to said one bimetal element, the other bimetal element being responsive to heat of said safety heater, said combustion switch contacts being carried by said bimetal elements to be normally engaged with each other when the bimetal elements are cold, while they are heating and cooling and while they are hot, armature and magnet means for producing snap action of, and tending to close said contacts, said bimetal elements upon the one heated by the safety heater remaining heated and the other one cooling, opening said contacts, and upon said other one remaining cold and the one heated by the safety heater being heated, opening said contacts a predetermined time period after the safety heater is energized, said room thermostat circuit including a relay coil serially connected with said safety heater and initially with the end terminals of said secondary, said relay being constructed to close said burner switch when energized in response to closure of said room thermostat, and means operated by said relay upon energization thereof to connect the tap of said secondary to said room thermostat circuit between said safety heater and said combustion switch to thereby reduce the holding current in said relay coil and enable the same to open upon a predetermined minimum fall of line voltage.

2. In a burner system, a transformer, an initial room thermostat circuit including a room thermostat, means operable upon energization by the secondary of said transformer to initiate operation of the burner, a safety heater and combustion switch contacts, a pair of temperature responsive elements carrying said combustion switch contacts, one of said elements being responsive to the heat of said safety heater and the other being located exterior of and responsive to heat radiated from a combustion chamber, said combustion switch contacts being normally

engaged when the temperature responsive elements are either cold or hot and disengaged only when the safety heater heated one is hot and the combustion chamber heated one is cold, said safety heater and said contacts being included in said initial room thermostat circuit whereby (1) upon closure of the room thermostat, operation of the burner is initiated; (2) upon heating of both of said temperature responsive elements the burner circuit is maintained energized; (3) upon separation of said combustion switch contacts as a result of combustion failure after it has occurred the room thermostat circuit is opened at the combustion switch, and (4) upon heating of the temperature responsive element heated by the safety heater and the temperature responsive element heated by the combustion chamber remaining in its cold position said combustion switch contacts are opened after a time period determined by the effect of the safety heater on the temperature responsive element heated thereby, a second circuit energized by a portion only of said secondary of said transformer and including said room thermostat, said relay coil and said combustion switch contacts, holding contacts for establishing said second circuit and for maintaining it as long as said combustion switch contacts are engaged with each other, said holding contacts being closed by energization of said means, and a third circuit energized by the remaining portion of said secondary and including said safety heater only, said second and third circuits being established and said initial room thermostat circuit being altered as to current supplied thereto by closure of said holding contacts.

3. In a burner protection system, a transformer, an initial room thermostat circuit including a room thermostat, means operable upon energization by the secondary of said transformer to initiate operation of the burner, combustion switch contacts, a pair of temperature responsive elements therefor, a heater for one of said temperature responsive elements, the other one being responsive to the temperature of a combustion chamber and being located between the combustion chamber and said one of said temperature responsive elements, and a control circuit interconnecting the foregoing elements and operating upon closure of said room thermostat to (1) energize said means and thereby operate the burner and to energize said heater, and (2) to open said room thermostat circuit at said combustion switch contacts when they are separated by combustion failing to occur or failing after occurrence, a second circuit energized by a portion only of said secondary of said transformer and including said room thermostat, said combustion switch contacts and said means, holding contacts for establishing said second circuit and for maintaining it as long as said combustion switch contacts are engaged, said holding contacts being closed by energization of said means, and a third circuit energized by the remaining portion of said secondary and including said heater only, said second and third circuits being established and said initial room thermostat circuit being altered as to the current supplied thereto by operation of said means as a result of room thermostat closure effecting closure of said holding contacts.

4. In a control system for burners including a protection feature, a transformer having an intermediate tap for furnishing two sources of current supply, an initial room thermostat circuit

connected across said transformer and including a room thermostat to initiate operation of the burner, a heating element and a combustion switch in said initial room thermostat circuit, said combustion switch comprising a pair of bimetal elements and a pair of contacts, one of said contacts being carried by each element, one of said elements being responsive to combustion chamber temperatures and located outside of the combustion chamber, and the other being responsive to heat from said heating element and located between said heating element and said first element with the first element between said second element and the combustion chamber, an armature carried by one of said bimetal elements, a magnet cooperating therewith and carried by the other bimetal element to keep said contacts in engagement and effect snap action thereof toward open position when the energy in said bimetal elements is such as to overcome the pull of the magnet on the armature, holding contacts closed by energization of said means and connected with said initial room thermostat circuit for dividing it so that upon closure of the holding contacts a second circuit is established through said room thermostat, said means and said combustion switch contacts, and a third

circuit is established through said heating element, said combustion switch contacts, upon opening, discontinuing said third circuit.

5. A control system of the character described comprising a transformer, a room thermostat circuit including combustion switch contacts and a heater, a combustion switch including said contacts and a pair of temperature responsive elements, one of which responds to said heater 10 and the other located exterior of and responding to temperature radiated directly from a combustion chamber, a relay operable upon energization to cause operation of the burner, a circuit including the secondary of said transformer and 15 said relay and controlled by a room thermostat which establishes said circuit upon closure of the thermostat, and means thereafter operable to maintain said relay energized from one portion only of said secondary and said heater energized 20 from the remaining portion thereof, said temperature responsive elements being effective to normally retain said combustion switch contacts engaged when both temperature responsive elements are cold or hot, and to open them when 25 the one heated by the heater is hot and the one heated by the combustion chamber is cold.

BURTON E. SHAW.
